UNITED STATES PATENT OFFICE.

WINFRED JACOBS, OF DODGE CITY, KANSAS, ASSIGNOR TO AMERICAN TRACTOR,
FOUNDRY AND MANUFACTURING COMPANY, OF WICHITA, KANSAS.

METHOD OF FORMING STACKS.

1,366,387.

Specification of Letters Patent. Patented Jan. 25, 1921.

Application filed March 14, 1919. Serial No. 282,632.

To all whom it may concern:

Be it known that I, WINFRED JACOBS, a citizen of the United States, residing at Dodge City, in the county of Ford and

5 State of Kansas, have invented certain new and useful Improvements in Methods of Forming Stacks; and I do declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

This invention relates to a method of forming stacks of grain as it is harvested. In carrying out my invention I initially form the stack in a stack former which, in 20 practice, may consist of a wagon having sides, bottom and ends which are so constructed that initially an inverted stack is formed, which, upon removal from the former, may, by impact with ground, reverse its contour to present a finished stack. In removing this stack, it may be initially compressed or baled so as to eliminate the 25 liability of disintegration thereof as it is removed from the former.

30 The device is so constructed that it may be hitched to a tractor or associated with a grain header so that the grain may be discharged from the header elevator into the stack former, and preferably tightly packed 35 during the process of forming the stack.

In the drawings,

Figure I is a vertical longitudinal sectional view through a stack former constructed in accordance with my invention.

40 Fig. II is an end view of the stack, preparatory to being removed from the former.

Fig. III is an end view of the finished stack.

Fig. IV is a fragmentary perspective view 45 of the rear end of the former.

Fig. V is a side elevational view of a stack former constructed in accordance with my invention.

Fig. VI is a detail perspective view of the 50 rear axle support and one of the radius rods, and

Fig. VII is a cross sectional view through the stack former.

In order to present a comprehensive explanation of the essential steps for carrying

out my method, I will describe in detail an approved apparatus by means of which the stack may be formed.

Referring now to the drawings by numerals of reference:

1 and 2 designate the side sills of a wagon body which constitutes the stack former, as will be presently explained. Extending lengthwise of the wagon, and positioned at its longitudinal center, below the side sills 65 1 and 2, is a center sill 3 connected to the side sills by transverse floor sills 4 and 5, the floor sills 4 and 5 being connected to the center sill 3 by tie-plates 6, as best seen in Fig. VII, and the outer ends of the sills 4 70 and 5 are connected to the side sills by tie-plates 7 and 8. The floor sills 4 and 5 support the flooring 9 which, as shown, is concave; that is, the sides of the floor diverge at a relatively wide angle toward the side 75 sills, the purpose of which will be apparent hereinafter.

Upstanding stakes or standards 10 and 11 are carried by the side sills and support the side walls which consist of strips 12 and 13 80 running longitudinally of the vehicle, there being end strips 14 at the front thereof which are also connected to the end stakes 10 and 11.

15 is an axle beam carrying axle 16 on 85 which are mounted front wheels, the beam 15 being connected to the front of the vehicle by the tie beam 17 and braces 18.

At the rear of the vehicle are stub axles 19 and 20 which are connected to the side 90 sills 1 and 2 by suitable clips 21 and these axles extend through the diamond-shaped bracket plates 22 and 23, one of which is shown in detail in Fig. VI as being secured to one of the side sills by bolts 24 and to a 95 standard or stake by a bolt 25. The plates 22 and 23 extend below the side sills 1 and 2 and are connected to a truss rod 26 upon which the center sill 3 may rest, said truss rods and plates being reinforced by struts 27 100 and 28, as best seen in Fig. VII. The plates are also connected to radius rods. The rear standards 10 and 11 are somewhat larger than the remaining ones and these are connected by a cross bar 29 to which, with the 105 standards which it connects, are secured the side bars 30 and 31 of a yoke frame formed by the bars 30 and 31 and the cross bar 29. The yoke frame side bars 30 and 31 may consist of angles bent at the lower end in the 110

form of loops 32 (see Fig. VI) to embrace the stub axle so as to support the outer ends, the inner ends being supported by the yokes 21. The axles are further braced by the 5 radius rods 33 which are fastened to the side bars 30 and 31 and to the side rails 1 and 2, one of these being shown in Fig. VI, therefore, the rear sills 34 and 35 may be securely supported upon the axles 19 and 20. 10 To the rear end of the wagon or former are secured skids 36, there being an appropriate number, as best seen in Figs. I and IV, and the rear end of the vehicle is normally closed by the swinging gates 37 and 15 38. 39 is a cable or rope which constitutes a baling tie or compressor for the stack after it has been formed and which also assists in removing the stack by having its ends connected to a stake or anchor 40 which may be conveniently driven into the ground adjacent to the location of the stack.

In practising the invention, the gates are closed with the skids 30 folded against them, the whole being secured by the cross bar 41 in the cleats 42. The grain, grass or other material to be stacked will then be deposited in the former either by hand or by a header elevator, it generally being desirable to have an operator in the former to 25 evenly distribute and stomp the material as it is received so that it will stack to the best advantage. It is to be understood that it is desirable to lay a strong cable upon the center sill the entire length of the former 30 and have a loose end of sufficient length to partially encircle the stack after it is formed so that the two loose ends may be secured to the stake 39, as shown in Fig. I. After the stack is formed, as shown in Fig. II, 35 the free ends of the cable may be secured to the stake 39, it being understood, of course, that the gates 37 and 38 have been opened and the skids 36 rest upon the ground, as shown in Fig. IV. Power is 40 then applied to the former so that it is moved lengthwise of the stack, leaving the stack anchored to the stake 39.

As the former leaves the stack, it will 45 slide down the skids 36 and be deposited upon the ground. As the convex portion of the stack strikes the ground, the two upwardly curved sides will move down to rest upon the ground and since the stack is thicker at its longitudinal center than at 50 the edges, the contour of the stack will be reversed, as shown in Fig. III so that the top will have a curved water-shedding slope

which will be automatically formed by bringing the stack into contact with the ground. 60

The rope or cable may then be removed and the former continue in operation to form another stack.

It would be apparent that if the grain is cut from the outside of the field toward the center and the harvester and former travels so as to cut a continuous swath on all four sides of the field, a stack may be deposited or a number of stacks may be deposited, during the travel of the machine. 65 The next time around, another stack will be formed adjacent to the one previously deposited so it is obvious that in a large field, the stacks may be deposited in multiples uniform distances about the field so that 70 with my device the stacks will be automatically positioned. 75

The exact form and proportion of the device may vary but I have found in actual practice that a vehicle in the following proportions admirably serves the purpose intended: length, 20 feet; width, 9 feet; height, 80 9 feet; skids, 5 feet in length.

In order to eliminate liability of binding of the stack in the former when it is desired to remove it, I generally construct the front end slightly narrower than the rear end so the initial movement of the stack toward the rear end will relieve the pressure and consequently the friction 85 90 against the sides of the stack.

Having thus described my invention, what I claim as new therein, and desire to secure by Letters-Patent is:

1. The method of constructing stacks 95 which consists in collecting grain in a traveling former having a concave bottom whereby the stack will be formed with a convex base, temporarily binding the stack, withdrawing the stack longitudinally from the 100 former to a plane support to permit the stack to flex so that the convex portion will be at the top, and removing the binder.

2. The method of constructing stacks 105 which consists in collecting grain in a traveling former having a concave bottom whereby the stack will be formed with a convex base, binding the stack, withdrawing the stack longitudinally from the former to a plane support to permit the stack to flex 110 so that the convex portion will be at the top.

In testimony whereof I affix my signature.

WINFRED JACOBS.
